UNITED STATES PATENT OFFICE.

JOHN F. JANISCH, OF KIRKSVILLE, MISSOURI.

AUTOMATIC SELF-LOCKING FOLDING TABLE.

Application filed November 10, 1921. Serial No. 514,382.

To all whom it may concern:

Be it known that I, JOHN F. JANISCH, a citizen of the United States, residing at Kirksville, in the county of Adair and State 5 of Missouri, have invented a new and useful Automatic Self-Locking Folding Table, of which the following is a specification.

This invention relates to folding tables particularly designed for use in giving osteopathic treatments.

One of the objects of the invention is to provide a table made up of movably connected sections having means whereby they are prevented from sagging at their inner 15 or connected ends, the legs of the table being so mounted that when the table sections are folded together, the said legs will also be folded inwardly so that the table can thus be stored in a small space.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a central longitudinal section through the table, the same being set up for use.

Figure 2 is a longitudinal section showing the table folded.

Figure 3 is a section on line 3—3, Figure 1.

Figure 4 is a section on line 4—4, Figure 1.

Figure 5 is a longitudinal section through a modified form of table.

Referring to the figures by characters of reference 1 and 2 designate the sections of the table top, said sections being provided with side flanges or aprons 3 extending downwardly therefrom and which are connected near their lower edges at the inner ends by links 4, one link being provided at each side of the table.

Pivotedly connected to the outer end portion of each of the aprons 3 is a leg 5, the two legs at each end of the table being connected by a cross strip 6, thus to provide a rigid structure. Each leg 5 has a plate 7 attached

to the outer side thereof and constituting a bearing and a spacing element as shown in Figure 4. The pivot pin 8 extends through this plate and also through the leg 5 and 60 the apron 3 as shown in said Figure 4. An arm 9 is extended upwardly and inwardly from each of the plates 7 and to each of these arms is pivoted a link 10. Each link, in turn, is pivotally connected as at 11, to one 65 end of a tie 12 which extends under the inner portions of the table sections 1 and 2, the two ends of the tie being inclined so as to diverge upwardly as shown at 13 and each of said ends having a longitudinal slot 14 70 into which extends a guide lug 15 projecting inwardly from the apron 3. It is to be understood that one tie 12 is provided adjacent each side of the table and that one link 10 at each end of the table is connected 75 to one of these ties while the remaining links are connected to the respective ends of the other tie.

A hanger 16 is pivotally connected to the center of the link 4 and has laterally extending arms 17 from the upper edge of which are extended laterally projecting stop yokes 18. A pivot stud 19 is extended laterally from the hanger 16 between the arms 17 and on this stud are mounted the members of the tie 12. It will be noted that this tie is formed of oppositely extended portions which lap the arms 17 and are mounted at theirlapping ends upon the stud 19. When the table is extended for use the yokes 18 bear downwardly on the members or portions of the ties 12. Thus the pivotally connected ends of the members of each tie cannot swing downwardly under the thrusts exerted through the hangers 16 90 because this would necessitate upward swinging of the members of the ties against and past the yoke 18. Consequently the yokes 18 and the pivot studs 19 will cooperate with the ties to properly support the inner ends 95 of the table section and at the same time the links 10 and the parts to which they are connected will hold the legs 5 against swinging movement.

When it is desired to fold the table the inner ends of the sections 1 and 2 are pulled upwardly. This will cause the hangers 16 to pull on the studs 19 and cause the members of the ties 12 to fold together between the folding table top sections. During this movement the studs 15 will slide in the slots 110 14 and, because of the movement of the sec-

tions 1 and 2 relative to the ties 12 thrusts will be exerted through the links 10 against the arms 9 with the result that the legs 5 will be swing inwardly between the sections 1 and 2 and the parts thus assume the position shown in Figure 2.

To open up the table for use it becomes merely necessary to swing the sections 1 and 2 apart whereupon the legs will swing outwardly and the yokes 18 will move onto the tie members or sections so that the parts will be positioned as shown in Figure 1.

If desired the outer end of one of the sections, 2, can be provided with a foot rest 15 20 while a head rest 21 may be connected to the legs 5 supporting the other section 1. This head rest can be mounted on an angular extension 22 pivotally connected to the legs as shown at 23. A notched supporting 20 bar 24 is pivotally connected to the extension and adjustably engages a cross rod 25 attached to the legs. Thus the head rest 21 can be held at any desired angle relative to the table top. As shown in Figure 2 the 25 foot board and the head rest will not interfere with the folding of the table.

In Figure 5 another modified front section has been illustrated. In this form of the 30 device the table sections 26 and 27 are connected by side links 28 similar to the links 4 and to these links are pivoted hangers 29 similar to the hangers 16 hereinbefore referred to. Each of the sections 26 and 27 has connected legs pivotally attached to the 35 outer end portion thereof and these legs are further attached to the sides of the sections by braces consisting of links 31 and 32 pivotally attached to an intermediate link 33 having a flange 34 constituting an abutment 40 for the links 31 and 32 to hold the several links substantially in alignment while the table is in use.

Each of the links 31 is slotted longitudinally as indicated at 35 and is pivotally and 45 slidably engaged by a stud 36 extending from one end of a tie 37 corresponding with the tie 12, the two ties being pivotally attached to the hangers 29 as shown at 38. The outer end portions of the ties are offset upwardly 50 and slotted as shown at 39 to receive guide studs 40 extending inwardly from the sides of the sections 26 and 27.

Secured to the bottom portion of the section 26 are one or more inclined guide rods 55 41 on each of which is slidably mounted a

sleeve 42 connected by a link 43 to the legs 30. The headrest 44 is pivotally attached to the sleeve 42 and slidably mounted on a supporting rod 45. Thus it will be seen that when this form of table is folded with the 60 legs 30 extending toward each other and under the sections 26 and 27 and said sections are folded together as in the structure illustrated in Figure 2, the sleeve 42 will be shifted longitudinally along the rod 41 by 65 the link 43 with the result that the headrest 44 will be retracted to position under the section 26. When, however, the table is set up for use the movement will be reversed and the headrest 44 will be projected to the position illustrated in Figure 5.

What is claimed is:—

1. A folding table including top sections, links connecting the same, legs pivotally connected to the sections adjacent the outer 75 ends thereof, foldable ties supported by the links and slidably and pivotally engaging the top sections, stop devices supported by the links for engagement by the ties to support the inner ends of the top sections in extended or active positions, and foldable 80 braces connecting the top section and the legs and pivotally and slidably engaged by the ties for folding the legs inwardly between the top sections when said sections are folded together.

2. A folding table including top sections, links connecting the same, legs pivotally connected to the sections adjacent the outer 90 ends thereof, foldable ties supported by the links and slidably engaging the top sections, stop devices supported by the links for engagement by the ties to support the inner ends of the top sections in extended or active positions, and means connecting the ties and the legs for folding the legs inwardly between the top sections when said sections are folded together, a guide device connected to one of the top sections, a headrest attached thereto, means carried by said top section for supporting the headrest, and means operated by the folding of the legs for sliding the headrest upon its supporting and guiding means to position beneath said top section.

In testimony that I claim the foregoing as my own, I have hereto affixed my signature.

JOHN F. JANISCH.
